UNITED STATES PATENT OFFICE.

CALEB M. PEELLE, OF BROOKLYN, NEW YORK, ASSIGNOR TO THE PEELLE CO., OF NEW YORK, N. Y., A CORPORATION OF NEW YORK.

LATCH FOR ELEVATOR-DOORS.

1,032,498.

Specification of Letters Patent. Patented July 16, 1912.

Application filed July 6, 1910. Serial No. 570,590.

To all whom it may concern:

Be it known that I, CALEB M. PEELLE, a citizen of the United States, and resident of Brooklyn, in the county of Kings and State of New York, have invented certain new and useful Improvements in Latches for Elevator-Doors, of which the following is a specification.

The invention relates to improvements in latches for elevator-doors, and is particularly designed for use in connection with self-closing fireproof doors, severally arranged in two parts or sections and supported for vertical movement from and toward each other for opening and closing a doorway leading to an elevator-shaft; and the object of the invention is to provide a latch adapted to engage the door for holding it open when the car is suitably positioned, and to release the same for its automatic closing when the car is shifted from such position; and a further object comprehends independent means including a fusible-link connection actuated by an adjacent fire or extreme heat for releasing the latch to permit the door to close if casually left open.

In describing the invention in detail reference is had to the accompanying drawing, forming a part of this specification, and wherein like characters of reference are used to designate like parts throughout the several views, and in which:

Figure 1 is a front elevation of an elevator-doorway, having upper and lower door sections suitably connected together and provided with the improved latch embodied in the present invention; Fig. 2, a transverse section of the doorway, shown in relation with the latch; Fig. 3, an enlarged ground plan of the latch, with the adjacent parts shown partially in section; and Fig. 4 is an enlarged side view of the latch.

Numerals 1 and 2 designate respectively the adjacent portions of the upper and lower sections of a two-part fire-proof elevator-door, to the lower section of which is secured a carrier-bar 3, connected at its opposite ends to the flexible bands or chains 4, which lead over the carrier-wheels 5 and are secured to the upper door-section. The wheels are mounted upon guide-rails 6, which are fixed to the wall of the elevator-shaft and provided with interior angles 7 for slidably receiving the guide-blocks 8, secured to the door-sections, which as thus

mounted are adapted for vertical movement from and toward each other for opening and closing a doorway 9, leading to the elevator-shaft, the upper door-section being more heavily constructed to have an overbalancing effect upon the lower section to cause a self-closing action of the door when opened.

Within the elevator-shaft is movably supported a car of ordinary construction, indicated by the fragmental portion of an upright 10 and a platform 11, to the latter of which is fixed a double cam, having the raised faces 12 and the depressed part 13.

Upon one of the guide-rails 6 is fixed an angle frame 14, carrying a pin 15 for pivotally supporting a latch-lever, on the upper arm of which is formed a hook 16 and an actuating-lug 17. The latch-lever is provided with a lower actuating-arm 18, adapted to be engaged by a bolt 19, slidably mounted in guides 20, fixed upon the angle frame 14. Also fixed to the frame is a spring 21 which tends to outwardly urge or project the hook end of the latch for engagement with the carrier-bar 3, secured to the lower door-section 2. To the upper end of the bolt 19 is fixed an eye-bolt 22, to which is connected the upper end of a tension-spring 23, the lower end of the latter being secured to a bracket 24, fixed to the angle frame. Also to the upper end of the bolt 19 is secured one end of wire 25, the opposite end of which passes through a perforation 26 in the guide-rail and is secured to a fusible-link 27, fixed to the lintel 28 of the doorway, exterior of the elevator-shaft. The fusible-link is of ordinary construction and by means of the connection-wire is normally adapted to retain the bolt in its upper position against the action of the tension-spring 23 and out of engagement with the latch-lever.

During the disengagement of the bolt, as shown, the latch is free to be actuated by the movement of the car through the cam-faces 12, fixed to the floor thereof, and when the latter is suitably positioned, on the level with the sill of the doorway, as shown, the recess 13 of the cam will be in line with the actuating-lug 17 of the latch-lever, in which position the hook portion 16 of the lever is normally projected by the spring 21 and is adapted to engage the carrier-bar 3 of the lower door-section when the latter is manually depressed for opening the door. Upon

the movement of the car in either direction, the cam engages the actuating-lug for the disengagement of the hook from the carrier-bar to permit the door to close by gravity.

5 As thus arranged, it will be obvious that an elevator-door cannot be conveniently opened or remain open unless the car is suitably positioned in relation thereto, and furthermore, if casually left open in such position, the latch will be independently actuated in case of an adjacent fire or extreme heat to close the door by the melting of the fusible-link 27 and the release of the spring-actuated bolt 19.

10 15 What I claim as my invention and desire to secure by Letters Patent, is:

1. The combination with an elevator-shaft having a doorway leading thereto, of a self-closing door for said doorway, a spring-projected latch normally adapted to normally retain said door in open position, an elevator-car, means for retracting said latch by the movement of said elevator-car, and latch-retracting means including a fusible-link connection adapted to operate independently of said car.

2. The combination with an elevator-shaft having a doorway leading thereto, of a manually-opened self-closing door for said doorway, a latch mounted adjacent said door and normally held for engagement thereby, an elevator-car, a double cam secured to said car for engagement with said latch, said cam having double raised working faces and an intermediate depression, whereby the door is held in open position when the car is aligned with respect thereto, and automatically closes when the car is moved from such position, and means including a fusible-link 40 for releasing said latch and operating inde-

pendently of said car-closing means when the car is aligned with respect to said door.

3. The combination with an elevator-shaft having a doorway leading thereto, of a self-closing door for said doorway provided with a carrier-bar, a latch-lever pivotally mounted adjacent said carrier-bar and having an upper arm provided with a hook and an actuating-lug, and an oppositely-disposed lower actuating-arm, a spring normally urging the hook of said upper arm into engagement with said carrier-bar, an elevator-car, a cam mounted on the car for engagement with the actuating-lug, a spring-actuated bolt slidably mounted for engagement with the actuating-arm of said latch-lever, a fusible-link secured adjacent said doorway, and a connection between said fusible-link and bolt adapted to hold the latter out of engagement with the actuating-arm of the latch-lever 60 against the action of its spring.

4. The combination with an elevator-shaft having a doorway leading thereto, of a self-closing vertically slidable door for said doorway, an elevator-car, spring-actuated latch mechanism for holding the door in open position while the car is at rest at that floor of the building, means on the car to release said latch mechanism and allow the door to close when the car leaves the floor in either direction, and latch-retracting means including a fusible link connection adapted to release the door independently of the car.

Signed at New York city in the State of New York this 29th day of June A. D. 1910. 75

CALEB M. PEELLE.
